UNITED STATES PATENT OFFICE.

FRANK L. ZYBACH, OF GRAND ISLAND, NEBRASKA.

AUTOMATIC TRACTOR-GUIDE.

1,390,419.

Specification of Letters Patent. Patented Sept. 13, 1921.

Application filed October 8, 1920. Serial No. 415,588.

To all whom it may concern:

Be it known that I, FRANK L. ZYBACH, a citizen of the United States, residing at Grand Island, in the county of Hall and 5 State of Nebraska, have invented certain new and useful Improvements in Automatic Tractor-Guides, of which the following is a specification.

This invention relates to tractor guides 10 and the primary object of the invention is to provide an improved attachment for tractors, which will effectively guide the same during the plowing operation without the aid of an operator, thereby resulting in the saving of 15 time and labor.

Another object of the invention is to provide an improved automatic steering attachment for tractors during the plowing operation, which is so constructed that the travel 20 of the tractor will be automatically stopped when the tractor becomes out of alignment with the previously plowed furrow, or when the plow becomes accidentally detached from the tractor.

25 A further object of the invention is to provide an improved guide or pilot head for the tractor steering attachment, said pilot or guiding head being so constructed that the likelihood of the same riding out of the furrow is reduced to a minimum.

30 A further object of the invention is to provide an automatic means for stopping the operation of the tractor when the plows become clogged with debris, thereby insuring 35 a clean cut furrow for the guide or pilot head.

40 A still further object of the invention is to provide an improved automatic steering attachment for tractors during the plowing 45 operation which is so arranged that the tractor engine will be automatically stopped under any conditions out of the ordinary, thereby absolutely eliminating accidents or crooked furrows.

50 With these and other objects in view, the invention consists in the novel construction, arrangement and formation of parts as will be hereinafter more specifically described, claimed and illustrated in the accompanying 55 drawings, forming a part of this specification, in which drawings:

Figure 1 is a plan view of a tractor and plow illustrating the improved steering means incorporated therewith.

55 Fig. 2 is an enlarged fragmentary side elevation of a tractor showing the improved

steering means attached thereto and illustrating the pilot or guide head in steering position.

Fig. 3 is an enlarged fragmentary plan 60 view illustrating the means of incorporating the improved attachment with the steering connecting rod and stub steering axles of a tractor.

Fig. 4 is an enlarged fragmentary longitudinal section through a tractor having the improved attachment connected thereto, and showing more particularly the switch for automatically cutting out the operation of the motor if any accident befalls the plows 70 or pilot head.

Fig. 5 is a view similar to Fig. 3 illustrating the position of the pilot head and switch member if the steering wheels of the 75 tractor are turned too far to the left.

Fig. 6 is a view similar to Fig. 5 illustrating the position of the pilot head and automatic cut out switch when the steering 80 wheels of the tractor are turned too far to the right, and

Fig. 7 is a fragmentary side elevation of the plows illustrating the means of connecting the emergency cable with the plows and showing the position of the emergency 85 cable when the plows become clogged with debris.

Referring to the drawings in detail, wherein similar reference characters designate corresponding parts throughout the several 90 views, the letter A indicates a tractor, B, the plow, and C the improved automatic guiding attachment for the tractor and plow.

The tractor A may be of any preferred make, size or style, and as shown includes the body 10 having the rear drive wheels 11, 95 the front steering wheels 12 and the motor 13. The steering wheels 12 are mounted in the usual manner upon the stub axles 14 which are in turn swivelly carried by the end of the dead axle or beam 15. The stub 100 axles 14 are provided in the ordinary manner with the rearwardly extending guide arms 16, which are connected by the connecting rods 17. The steering arm 18 of the stub axles have connected thereto in the usual 105 manner the steering rod 19, which is operated by the steering wheel 20.

The plow B may be of the usual or any preferred type used in tractor plowing and as shown includes the wheeled supporting 110 frame 21, the inner and outer plow beams 22 and 23. The inner and outer plow beams

22 and 23 support the usual type of plows 24 and 25. The plow B is connected in any preferred manner to the tractor A as shown in Fig. 1 of the drawings.

5 The improved attachment C for automatically steering the tractor comprises an arm 30 which is secured to the forward end of the steering arm 16 of the right hand side of the tractor. The arm 30 extends forward 10 of the steering wheel 12 on the right hand side of the tractor and terminates in a right angularly extending pin 31. This pin 31 is arranged directly in front of the right hand steering wheel and rotatably receives 15 the sleeve 32 of the rod 33 of the pilot head 34.

The pilot head 34 is of a simple construction and is so formed as to engage in the furrow in advance of the steering wheel for 20 guiding the tractor. The construction of the pilot head 34 is such that the possibility of the same riding out of a furrow is reduced to a minimum. As shown, this head 34 is formed by bending the free lower terminal 25 of the rod 33 into a substantially U-shape as designated by the numeral 35. The bottom of the U is bent slightly toward the left for engagement with the furrow, and the terminal thereof leans slightly away 30 from the furrow wall. An arcuate iron shield 37 is carried by the head 34, and projects outwardly from the right side of the U as clearly shown in the drawings. It also 35 can be seen by referring to Fig. 2 of the drawings that the guide rod 33 curves downwardly and forwardly from the pin 31.

Thus it will be seen that the pilot guide head 34 riding in the furrow will effectively turn the guide wheels to the right or left 40 according to the direction of the furrow.

A cable 40 is secured at 41 to the plow beam 23, directly above the plow share 25, and this cable is trained around a guide pulley 42, which is carried by a supporting rod 45, which is clamped as at 44 to the axle beam 15. The forward end of the cable is secured by means of a coupling 45 to the cross connecting rod 17. This cable has interposed therein adjacent to its forward end, 50 a contractile coil spring 46 and this spring is under sufficient tension so as to normally hold the pilot head 34 in engagement with the land side of the furrow. This will effectively permit the guiding of the tractor by 55 means of the pilot head.

A switch member 50 is adapted to be operated by the pilot head 34 for stopping the operation of the motor 13 if the pilot head 34 rides out of the furrow or if the plow B 60 becomes accidentally detached from the tractor. This switch mechanism 50 is interposed in the ignition system of the motor 13 and includes a stationary spring contact 51 and a removable contact 52. The contacts 65 51 and 52 are connected by means of wires

53 and 54 with the ignition system. The movable contact 52 is carried by the insulated ends 55 of the arm 56 of a three armed lever 57. This three armed lever 57 is secured for movement on the shaft 58' 70 upon which is keyed the guide pulley 42. The wires 53 and 54 are connected in the ignition circuit of the motor 13 and when the movable contact 52 is in engagement with the stationary contact 51, the circuit 75 through the ignition system is closed. The arms of the three armed lever 57 extend at quarters from the hub of the lever and the arm 58 is arranged intermediate the arm 56 and the arm 59. The free end of the arm 80 58 is provided with spring fingers 60 which receive the headed end of the emergency rod 61. The inner end of the emergency rod 61 is secured by means of a clamp 62 to the cable 40, in rear of the spring 46. The provision of this emergency rod 61 permits the automatic stopping of the tractor when the plow becomes detached from the tractor or when the plow becomes clogged with debris as clearly shown in Fig. 7 of the drawings. 90 It can be seen that if the plow B breaks loose from the tractor, considerable strain will be placed upon the rod 61 which will turn the three armed lever 57 on the pivot pin or shaft 58' which will move the movable contact 52 out of engagement with the stationary contact 51. This immediately stops the operation of the motor. If the tension on the rod 61 is such that the three armed lever is swung beyond a predetermined point, the headed end of the rod will ride out of engagement with the spring fingers formed on the end of the arm 58 and thus prevent any damage being done to the three arm lever. 100

To insure that the furrow which is to be used as a guide furrow is free from all debris, the cable 40 has been so secured to the plow beam 23 that when debris collects on the plow, the same will be raised into engagement with the cable 40 and exert a tension on the same. This is shown in Fig. 7 of the drawings. This tension exerted on the cable 40 will in turn pull on the rod 61 and move the movable contact 52 from out 110 of engagement with the stationary contact 51 as heretofore described.

The free end of the arm 59 of the three armed lever 57 is provided with a headed pin 63 which is slidably mounted in a slot 64 120 formed in the free end of a connecting rod 65. This connecting rod 65 is pivotally connected as at 66 to the steering arm 16 and is so arranged that when the pilot head 34 rides out of the guide furrow and the steering wheels turn beyond a predetermined point as to cut off the motor of the tractor and thus prevent the tractor from running free in the field. During the ordinary running of the tractor and the turning of ordi- 125 130

nary corners at the terminals of the field, no movement of the arm 65 will be transmitted to the three armed lever 57 owing to the slot 64. However, when the wheels are turned 5 beyond a predetermined point, either to the left or right as shown in Figs. 5 and 6 of the drawings, the arm 65 will be moved beyond a predetermined point and swing the three armed lever on the pivot pin or shaft 58' 10 which will cause the contact 52 to be moved out of engagement with the contact 51. This causes the breaking of the ignition circuit.

From the foregoing description, it can be seen that a very effective and simple arrangement has been provided for automatically guiding a tractor during the plowing operation and which is so arranged in relation to the plow and tractor that in case of any emergency or accident, the tractor 15 engine will be automatically stopped.

It can be seen that when the tractor makes a turn to the left, the distance between the front part of the tractor A and the right hand plow share 25 is naturally increased, 20 which draws the cable 40 somewhat tighter, thereby increasing the tension of the spring 46. The tension of the spring 46 is thus increased just when it is most needed to turn the wheels to the left, causing the 25 pilot head 34 to run close to the left side of the furrow while making the curve, thus keeping the tractor in a true course around the field. If, on the other hand, the tractor is making a turn to the right in a furrow, 30 it causes the cable 40 to slack a little which relieves some of the tension on the spring 46 thus allowing the guide rod and pilot head to run more freely in the furrow. To facilitate the movement of cable 40 and to 35 prevent the dragging thereof on the ground, a guide 40' is secured to the tractor. A plurality of rearwardly extending guide fingers 40' are carried by the plow 24 so as to throw all debris to one side thereof and thus further insure the making of clean furrows.

Changes in details may be made without departing from the spirit or scope of this invention; but,

I claim:

50 1. In combination with a tractor including a steering mechanism and a plow, of an automatic actuating mechanism for said steering mechanism including a pilot member adapted to ride in a furrow and follow the curvature thereof, means operatively connecting the pilot member to the steering mechanism of the tractor, means for automatically stopping the tractor, when the pilot member leaves the furrow, and means 55 for automatically operating said last mentioned means upon accidental detachment of the plow from the tractor.

60 2. In combination with a tractor including a steering mechanism and a plow, of an automatic actuating mechanism for said

steering mechanism including a pilot member adapted to ride in a furrow and follow the curvature thereof, means operatively connecting the pilot member to the steering mechanism of the tractor, means for automatically stopping the tractor, when the pilot member leaves the furrow, and means for automatically operating said last mentioned means when the plow becomes clogged with debris. 75

3. In combination with a tractor including a steering mechanism and a plow connected to said tractor, of an automatic actuating device for said steering mechanism including a pilot member adapted to ride in a furrow, spring means for normally holding the pilot member in engagement with one wall of the furrow, means connecting the pilot member with the steering mechanism, means attaching the plow with the steering mechanism, and means actuated either by said plow connecting means or said pilot member for automatically stopping the operation of the tractor in cases of emergency. 90

4. In combination with a tractor including a steering mechanism, a driving motor having an ignition system, and a plow connected to said tractor, of an automatic actuating device for said steering mechanism including a pilot member adapted to ride in a furrow and follow the curvature thereof, means connecting the pilot member with the steering mechanism of a tractor, a cable connecting the plow with the steering mechanism, a switch interposed in the ignition system of the engine, and means actuated either by said cable or pilot member for operating said switch under certain conditions. 95

5. In combination with a tractor including a steering mechanism and an internal combustion engine having an ignition system, and a plow connected to said tractor, of an automatic actuating mechanism for said steering mechanism including a pilot member adapted to ride in a furrow, spring means normally holding the pilot member in engagement with one wall of the furrow, means operatively connecting the pilot member with the steering mechanism, a switch interposed in the ignition circuit including a movable contact and a stationary contact, a lever carrying said movable contact, a pin on said lever, a slotted arm arranged to receive said pin, means connecting the arm 100 to the steering mechanism, a cable connecting the plow with the steering mechanism, and means connecting the cable with the lever carrying the movable contact. 110

6. In combination, a tractor including a 125 steering mechanism having a pair of stub axles, steering arms carried by the stub axles, and a rod connecting said steering arms, and an internal combustion engine having an ignition system, and a plow con- 130

nected to said tractor, of an actuating device for the steering mechanism including a forwardly extending rod connected to one of said steering arms, a steering rod connected to said arm for swinging movement in a vertical plane, a pilot head connected to said steering rod, a switch interposed in said ignition circuit including a stationary contact and a movable contact, a cable connecting the plow and the rod connected to the steering arms, a movable three arm lever, means connecting the movable contact with one of the arms, a pin carried by another one of said

arms, a slotted rod slidably receiving said pin, means connecting the slotted rod with 15 said mentioned steering rod, a contractile coil spring interposed in said cable, and an emergency rod connected to said cable in rear of said spring and to one of the arms of the tree arm lever. 20

7. In a tractor steering mechanism, a steering rod, a depending U-shaped terminal formed on said rod, and a guard shield extending around said U-shaped terminal.

FRANK L. ZYBACH.
